MULTIRING LIQUID FUEL BURNER

Filed May 31, 1930

UNITED STATES PATENT OFFICE

1,974,437

MULTIRING LIQUID FUEL BURNER

William Edward Taft, Athol, Mass.

Application May 31, 1930, Serial No. 457,853

19 Claims. (Cl. 158—87)

This invention relates to liquid fuel burners wherein the liquid fuel, as oil, is vaporized in a trough or channel and the vapors are burned between spaced and perforated combustion tubes or 5 chimneys which surround and upstand above the top opening of the channel.

It is now common to construct burners of this general type as is shown, for instance, in my copending application Serial No. 355,066, filed 10 April 15, 1929, wherein the oil is vaporized in a middle channel and some of the vapor is burned between combustion tubes located thereabove and some of the vapor is conducted into an outer vapor channel and is burned between combustion tubes 15 located above said outer channel. The inner channel functions to vaporize the oil and the outer channel constitutes only a vapor distributor channel after the burner is in steady operation.

In designing burners of this general type adapted to consume large quantities of oil and give off much heat, especially for use in house-heating boiler-furnaces, it has been proposed to provide a number of vapor channels arranged concentrically with each other around an innermost vaporizing channel and communicating ducts extended in series between the vaporizing channel and the outer vapor channels. It has been found, however, that such an arrangement has not been commercially successful since little vapor reached 25 the outer vapor channels and thus the added outer vapor channels did not materially increase the heating effect of the burner to the extent expected. As a consequence, it has been the custom, where more than two channels have been provided, to vaporize oil in each channel, thereby using each channel as a vapor generating channel. This arrangement has been in general unsatisfactory because of the increased surfaces on which carbon deposits can form and collect as the oil 30 vaporizes, and for other essential reasons.

It is an object of the present invention to provide an oil burner having a plurality of vapor channels and a vaporizing channel which is common to all of the vapor channels, the burner being 45 so arranged that vapor is supplied from the vaporizing channel equally to all of the vapor channels so that good combustion is provided in the combustion tubes associated with all of the channels and so that there is no appreciable starving 50 of any one channel.

In carrying out my invention, I so locate the vaporizing channel with respect to the vapor channels that vapor can flow independently from the vaporizing channel into each vapor channel 55 and also so that the vaporizing channel is equally spaced from the vapor channels and has separate passages communicating with each vapor channel independently of the other vapor channels, the passages being of practically equal length so 60 that vapor can flow as readily from the vaporiz-

ing channel into one vapor channel as into another vapor channel, thereby insuring good distribution of vapor to the vapor channels; and this constitutes a further object of the invention.

Another object of the invention is to locate the 65 vaporizing channel between and concentric with and equally spaced from two vapor channels, with vapor passages independently connecting the vaporizing channel with the vapor channels.

A further object of the invention is generally 70 to improve the construction and operation of liquid fuel burners of the type herein set forth.

Fig. 1 is a plan view of the base of a burner embodying the present invention.

Fig. 2 is a sectional elevation of the burner taken 75 along line 2—2 of Fig. 1.

Fig. 3 is a sectional detail taken along line 3—3 of Fig. 1.

The burner herein shown as embodying the present invention comprises a circular base having the annular open-top fuel-vaporizing channel or trough 10 provided with outer and inner upstanding side walls 12 and 14 respectively and the bottom wall 16. Annular vapor channels 18 and 20 are concentric with and are equally spaced 80 radially from the vaporizing channel 10. The outer open top vapor channel 18 consists of outer and inner upstanding side walls 22 and 24, respectively, and the bottom wall 26. The inner open top vapor channel 20 has similar upstanding outer 85 and inner side walls 27 and 28, respectively, and the bottom wall 30. The inner wall 28 surrounds an air passage 32 which is open at the top and bottom of the base so that air for combustion can pass upwardly therethrough. The vaporizing 90 channel 10 is wide in radial extent while the vapor channels 18 and 20 are narrow in radial extent. The vapor channels 18 and 20 are radially spaced from the vaporizing channel 10 by annular passages 34 and 36, respectively, which 95 are open at the top and also at the bottom of the burner base so as to admit the passage of combustion air upwardly between the channels. The channel 18 is connected with the vaporizing 100 channel 10 by six webs 38 which are equi-angularly spaced in and extend across the air passage 34. Said webs have vapor passages or ducts 40 therein by which the vapor generated in the vaporizing channel 10 can flow outwardly into the vapor channel 18. The vaporizing channel 10 and the 105 inner vapor channel 20 are similarly connected by three webs 42 which are located in the annular air passages 36 and are equi-angularly spaced therein and are disposed midway between the webs 38. Said webs 42 have passages or ducts 110 44 therein which conduct vapor from the vaporizing channel 10 into the inner vapor channel 20. Liquid oil is conducted into the bottom of the vaporizing channel 10 at a plurality of equally 115 spaced points therein and, as here shown, three 120

oil pipes 46 extend through the bottom wall 16 and open into the vaporizing channel at equi-
angularly spaced points therein which prefer-
ably are so located as to maintain a uniform
5 distribution of vapor in said vaporizing channel
with respect to the passages 40 and 44. The pipes
46 are connected by means, not shown, to a suit-
able source of oil supply that is or may be common
10 with the particular type of burner. The open top
of the vaporizing channel 10 is closed by a metal
generator cap 48. Said cap is in the form of a
flat ring and has a circular recess 50 in its inner
face in which the top of the wall 14 is located
15 so that the ring is seated upon said wall and has
a portion which extends somewhat into the top
portion of the vaporizing channel. Said cap ex-
tends horizontally over the major portion of said
channel and has an outer edge 52 which confronts
20 and is terminated close to the inner face of the
wall 12 so as to provide a relatively narrow an-
nular passage 54 out of which vapor can pass.
The cap 48 is provided with an inner circular
opening 56, the wall of which is practically flush
25 with that face of the wall 14 that forms a part
of the air passage 36, so that the opening 56 is
in register with said air passage. The outer por-
tion of the cap 48 is provided with an annular
seat which supports the bottom end of an up-
20 standing perforated combustion tube 58 which
thus forms a continuation of the passage 54. The
wall is provided with a seat which supports a
similar perforated tube 60 in concentric spaced
relation with the tube 58 so that an annular
35 combustion chamber 62 is provided therebetween.
Similar inner and outer concentric combustion
tubes 64 and 66 are seated upon the walls 22 and
24 of the vapor channel 18 and extend upwardly
thereabove and provide an annular combustion
chamber 68 in which the vapor rising from said
40 channel 18 is burned. Other outer and inner
concentric spaced combustion tubes 70 and 72 are
seated on and upstand above the walls 26 and
28 of the inner vapor channel 20 and form
an annular combustion chamber 74 which is in
45 communication with said channel 20.

The top of the inner tube 58 is closed by a cap
76 which preferably although not necessarily is
removable from the top of the tube. The space
50 between the tubes 58 and 70 is closed by an an-
nular ring 78 which preferably is removably seated
upon the tops of said tubes. Screws 80 pass
55 through said ring and are threaded into the gen-
erator cap 48 so that the ring 78 and the tube
58 are united and can be removed as a unit for
cleaning purposes. Another ring 82 is seated on
60 the tops of the tubes 64 and 60. The cover 76 and
the rings 78 and 82 close the tops of the air pas-
sages that are surrounded by the tubes and thus
cause the air to pass through the perforations
65 of the tubes and mix with the vapor in the
combustion chambers 74, 62 and 68, which cham-
bers are open at the top so that the hot products
of combustion can pass upwardly out of the
burner.

70 With the arrangement of the vaporizing and
vapor channels herein described, the vapor gen-
erated in the vaporizing channel 10 passes inde-
pendently into each of the vapor channels and
the vaporizing channel is equi-distant from the
75 two vapor channels so that both channels receive
a full amount of vapor whereby the combustion
is good at all of the channels. Thus the starving
of any one channel is prevented.

Many of the structural features of the burner
75 herein described, such for instance, as the con-

struction of the vaporizing channel 10, the cap
48, the cover rings 76, 78, 72, are claimed in my
above identified application and do not comprise
a part of the present invention except in combi-
nation with the novel construction and arrange-
ment herein described. 80

Heat from the vaporizing channel is transferred
85 through the walls of the conduits 38 and 42, and
also through interposed integral ribs 86 to the
vapor channels to heat and vaporize the oil there-
in, thus to facilitate the starting of the burner in
operation. When in steady operation, there is
90 liquid oil only in the middle, or vaporizing, chan-
nel.

I claim:

1. A liquid fuel burner having means providing
a vaporizing channel in which the liquid fuel is
vaporized, a plurality of vapor channels which are
normally free from liquid fuel when the burner
is in operation and which receive fuel vapor from
95 said vaporizing channel, means to admit liquid
into said vaporizing channel only, and means to
conduct the fuel vapor from said vaporizing chan-
nel independently into each of said vapor chan-
nels, all of said channels being open at the top
100 and having air passages therebetween, and com-
bustion tubes surrounding and upstanding above
the open top of said channels and in which the
vapor rising out of said channels is burned. 90

2. A liquid fuel burner having means providing
a vaporizing channel in which the liquid fuel is
vaporized, a plurality of vapor channels which are
normally free from liquid fuel when the burner
is in operation and which receive fuel vapor from
105 said vaporizing channel, means to admit liquid
into said vaporizing channel only, and means to
conduct the fuel vapor from said vaporizing chan-
nel independently into each of said vapor chan-
nels, said vaporizing channel being spaced equally
110 from all of said vapor channels, all of said chan-
nels being open at the top and having air passages
therebetween, and combustion tubes surrounding
and upstanding above the open top of said chan-
nels and in which the vapor rising out of said
115 channels is burned. 105

3. A liquid fuel burner having a plurality of
vapor channels, a vaporizing channel which is
equally spaced from all of said vapor channels
and has ducts which establish vapor communica-
120 tion independently between said vaporizing chan-
nel and each of said vapor channels, and means
to admit liquid fuel into said vaporizing channel
only, whereby the fuel is vaporized in said vapor-
izing channel and vapor thereof is conducted in-
125 dependently to each vapor channel, each channel
having a vapor outlet, and combustion tubes sur-
rounding and upstanding above said outlets in
which the vapor is burned. 120

4. A liquid fuel burner comprising a base hav-
ing three concentric open top circular channels
130 with concentric air passages between the chan-
nels, the intermediate channel being larger in
radial extent than said narrow outer and inner
channels and constituting a channel in which the
liquid fuel is vaporized, means to admit liquid
135 fuel into said intermediate vaporizing channel
only, said vaporizing channel having a plurality
of peripherally spaced passages which conduct
vapor to flow from said vaporizing channel into
said outer channel, said vaporizing channel also
140 having other circumferentially spaced inner pas-
sages which conduct vapor from said vaporizing
channel into said inner channel, and combustion
tubes surrounding and upstanding above the top
145 openings of all of said channels and providing
150

- combustion chambers therebetween in which the vapor rising out of said channels is burned.
5. A liquid fuel burner comprising a base having three concentric open top circular channels with concentric air passages between the channels, the intermediate channel being larger in radial extent than said narrow outer and inner channels and constituting a channel in which the liquid fuel is vaporized, means to admit liquid fuel into said intermediate vaporizing channel only, said vaporizing channel having a plurality of peripherally spaced passages which conduct vapor to flow from said vaporizing channel into said outer channel, said vaporizing channel also having other circumferentially spaced inner passages which conduct vapor from said vaporizing channel into said inner channel, and combustion tubes surrounding and upstanding above the top openings of all of said channels and providing 10 combustion chambers therebetween in which the vapor rising out of said channels is burned, said outer and inner vapor passages being staggered with respect to each other whereby to insure a good distribution of vapor independently into said outer and inner channels.
6. A liquid fuel burner comprising a base having three concentric open top circular channels with concentric air passages between the channels, the intermediate channel being larger in radial extent than said narrow outer and inner channels and constituting a channel in which the liquid fuel is vaporized, means to admit liquid fuel into said intermediate vaporizing channel only, said vaporizing channel having a plurality 20 of peripherally spaced passages which conduct vapor to flow from said vaporizing channel into said outer channel, said vaporizing channel also having other circumferentially spaced inner passages which conduct vapor from said vaporizing channel into said inner channel, and combustion tubes surrounding and upstanding above the top openings of all of said channels and providing combustion chambers therebetween in which the vapor rising out of said channels is burned, said outer and inner vapor passages being staggered with respect to each other whereby to insure a good distribution of vapor independently into said outer and inner channels.
7. A liquid fuel burner comprising a burner base having three concentric radially spaced endless open top channels which have concentric air passages therebetween, the intermediate channel being wider in radial extent than said outer and inner channels, which are radially narrow, said wide intermediate channel constituting a vapor generating channel and having a plurality of conduits which traverse said air passages and are circumferentially spaced and which establish vapor communication separately between said vaporizing channel and said outer and inner channels, the conduits communicating with said outer channel having openings into said vaporizing channel which are staggered with respect to the similar openings of the conduits communicating with said inner channel, means admitting liquid fuel into said vaporizing channel at a plurality of angularly spaced locations, a cap seated upon said base and overlying a substantial portion of the top opening of said vaporizing channel and providing said channel with an annular opening of reduced radial extent, and combustion tubes sur-
- rounding said channel opening and upstanding thereabove and providing combustion chambers in which the fuel rising through said opening is burned.
8. A burner of the class described having a base, a plurality of pairs of spaced, concentric, combustion tubes forming radially spaced interconnected, inner, outer and intermediate combustion chambers with intermediate air chambers between adjoining combustion chambers and a central air chamber within the inner combustion tube, a plurality of pairs of annular, spaced, upstanding walls on said base presenting between them concentric, spaced, inner, outer and intermediate fuel chambers underlying and communicating each with its respective combustion chamber, the intermediate fuel chamber being of greater width than the others, said base having openings to supply air to the central air chamber, the outer air chamber and the intermediate air chamber, a wall extending from one of the upstanding walls of said intermediate fuel chamber and overlying the latter and underlying the intermediate air chamber but having its peripheral edges spaced from the opposite upstanding wall of said intermediate fuel chamber to provide an annular opening aligned with the overhead combustion chamber, and means for supplying liquid fuel to the intermediate fuel chamber.
9. A burner of the class described having a base provided with a plurality of spaced interconnected fuel chambers comprising a relatively wide chamber and a relatively narrow chamber on each opposite side thereof, said burner having a plurality of pairs of combustion tubes forming spaced combustion chambers communicating one with each fuel chamber and having an intermediate air chamber between each adjoining combustion chamber and also an air chamber within said inner combustion tube, said base having openings to supply air to said several air chambers, said intermediate, wide fuel chamber having a wall overlying the chamber but underlying a part of the air chamber next adjacent said inner air chamber, said wall being spaced from the opposite walls of said fuel chamber to provide an opening therat into the overhead combustion chamber, and means for supplying liquid fuel to the intermediate fuel chamber.
10. A combustion tube burner having a base provided with open, concentric, relatively narrow, fuel channels, a spaced, intermediate, wider, fuel channel, a removable cover plate partly covering the intermediate fuel channel but leaving a narrow opening therein, combustion tubes in surrounding and upstanding relation to said opening, one of which is supported by said removable cover plate, other combustion tubes in surrounding and upstanding relation to each of said relatively narrow fuel channels, means for supplying liquid fuel to the intermediate channel, and fuel supply means between the intermediate and other fuel channels.
11. A combustion tube burner having a base provided with open, annular, concentric, relatively narrow, fuel channels, a spaced, intermediate, wider, fuel channel, a wall partly covering the intermediate fuel channel but leaving a relatively narrow opening at the top thereof, a pair of combustion tubes in surrounding and upstanding relation to the said narrow opening, and other pairs of combustion tubes in similar relation to said narrow fuel channels.
12. A burner of the class described having a

- base and a plurality of pairs of spaced concentric combustion tubes comprising radially spaced interconnected inner, outer and intermediate combustion chambers with intermediate air chambers between adjoining combustion chambers, a plurality of pairs of spaced, annular, upstanding walls on said base presenting between them concentric, spaced, inner, outer and intermediate fuel chambers underlying and communicating each with its respective combustion chamber, the intermediate fuel chamber being of greater width than the others, said base having openings to supply air to said intermediate air chambers, a wall extending from one of the upstanding walls of said intermediate fuel chamber and overlying the latter and underlying one of said intermediate air chambers but having its peripheral edges spaced from the opposite upstanding wall of said intermediate fuel chamber 20 to provide an annular opening aligned with the overhead combustion chamber, and means for supplying liquid fuel to the intermediate fuel chamber.
13. A burner of the class described having a base provided with a plurality of spaced fuel chambers comprising a relatively wide chamber and a relatively narrow chamber on each opposite side thereof, said burner having a plurality of pairs of combustion tubes forming spaced combustion chambers communicating one with each fuel chamber and having an intermediate air chamber between each adjoining combustion chamber, said intermediate wide fuel chamber having a wall overlying the chamber but underlying a part of one of said intermediate air chambers and spaced from the opposite side walls of said fuel chamber to provide an opening thereat into the overhead combustion chamber, means for supplying liquid fuel to the wider chamber, and fuel ducts connecting the wider chamber with both the remaining fuel chambers.
14. A burner of the class described having a base and a plurality of pairs of spaced concentric, combustion tubes forming spaced, inner and outer combustion chambers with an intermediate air chamber between said combustion chambers, a plurality of pairs of spaced, annular, upstanding walls on said base presenting between them concentric, spaced inner and outer fuel chambers underlying and communicating respectively with said inner and outer combustion chambers, the outer fuel chamber being of greater width than the inner chamber, said base having an opening between the two spaced fuel chambers to supply air to said air chamber, a wall overlying the outer wider fuel chamber and extending from the upstanding wall thereof next adjacent said air opening but having its peripheral edges spaced from the opposite upstanding wall of the wider fuel chamber to provide an annular opening aligned with the overhead combustion chamber, means for supplying liquid fuel to the outer chamber, and a fuel supply duct connecting the two chambers.
15. A burner of the class described having a base and a plurality of spaced, inner and outer combustion chambers with an intermediate air chamber between said combustion chambers, said base having inner and outer fuel chambers communicating respectively with said inner and outer combustion chambers, the outer fuel chamber being wider than the inner chamber and having a wall overlying the chamber but underlying a part of said intermediate air chamber and spaced from the opposite side walls of the fuel chamber to provide an opening thereat into the overhead combustion chamber, means for supplying liquid fuel to the outer chamber, and a fuel supply duct connecting the two chambers.
16. A burner of the class described having a base and a plurality of pairs of spaced, concentric, combustion tubes forming spaced combustion chambers with an intermediate air chamber between the combustion chambers, a plurality of pairs of spaced, annular, upstanding walls on said base presenting between them concentric, spaced, fuel chambers underlying and communicating each with one of the combustion chambers, one of said fuel chambers being of greater width than the other, said base having an opening between the two spaced fuel chambers to supply air to said air chamber, a wall overlying the wider fuel chamber and extending from the upstanding wall thereof next adjacent said air opening but having its peripheral edges spaced from the opposite upstanding wall of the wider fuel chamber to provide an annular opening aligned with the overhead combustion chamber, means for supplying liquid fuel to the wider chamber, and a fuel duct for supplying fuel from the wider chamber to the relatively narrow one.
17. A burner of the class described having a base and a plurality of pairs of combustion tubes forming spaced combustion chambers with an intermediate air supply chamber between said combustion chambers, said base having a plurality of fuel chambers underlying and communicating each with one of said combustion chambers, one of said fuel chambers being wider than the other and having a wall overlying the chamber and underlying a part of said intermediate air chamber, said wall providing an uncovered opening into the overhead combustion chamber adjacent the opposite side walls of the wider fuel chamber, means for supplying liquid fuel to the wider chamber, and a fuel duct for supplying fuel from the wider chamber to the relatively narrow chamber.
18. A burner of the class described having a base and a plurality of spaced interconnected, annular, combustion chambers with an intermediate air supply chamber between said combustion chambers, an annular fuel channel in said base beneath each combustion chamber, one of said channels being relatively wider than the other and having a wall overlying the channel and underlying a part of said intermediate air chamber but spaced from the opposite sides of said fuel chamber to provide a narrow opening, and spaced combustion tubes in surrounding and upstanding relation to said narrow opening.
19. A burner of the class described having a base and a plurality of spaced, annular, combustion chambers with an intermediate air supply chamber between the combustion chambers, said air chamber being closed at the top, an annular fuel channel in said base beneath each combustion chamber, one of said channels being relatively wider than the other and having a removable plate resting on the base overlying a part of said wider channel and underlying a part of said intermediate air chamber but spaced from the opposite sides of said wider fuel channel to provide a narrow opening, a fuel duct for supplying fuel from the wider channel to the relatively narrow channel, and means for supplying liquid fuel to the wider channel only.

WILLIAM EDWARD TAFT.
